UNITED STATES PATENT OFFICE.

FREDERICK MACDONALD FAIRGRIEVE, OF TORONTO, ONTARIO, CANADA.

COUPLING ELEMENT.

1,225,791.

Specification of Letters Patent. Patented May 15, 1917.

Application filed June 16, 1916. Serial No. 104,106.

To all whom it may concern:

Be it known that I, FREDERICK MACDONALD FAIRGRIEVE, residing in the city of Toronto, county of York, Province of Ontario, 5 Dominion of Canada, a subject of the King of Great Britain, have invented certain new and useful Improvements in Coupling Elements, of which the following is a specification.

10 My invention relates to improvements in coupling elements, and relates more particularly to the production of a hinge element whereby handles and like articles may be coupled to a door or other member, and the 15 object of my invention is to manufacture a coupling element from sheet metal in such a manner that the pivotal element will form an integral part of said element, and the construction of my preferred form of invention will be hereinafter particularly set forth, as well as a modification thereof, and what I claim as new will be pointed out in the claims forming part of this specification.

20 Figure 1 is a perspective view of my preferred form of coupling element as stamped out; Fig. 2 is a perspective view of this preferred form showing the element "buckled" to permit of the union therewith of the 25 member to be hinged or coupled thereto; Fig. 3 is a vertical cross-section through the front of an oven forming part of a gas stove, showing my coupling element used to hinge a handle to the door of the said gas 30 stove, and Fig. 4 is perspective view of a modified form of my coupling element, showing the same adapted to the coupling of two members together, disposed substantially at right angles each to the other.

35 In the drawings, like characters of reference indicate corresponding parts in each figure.

40 In putting my invention into practice, I take a piece A of sheet metal of the desired 45 gage, and stamp thereout of two holes B which are spaced apart and in alignment as illustrated in Fig. 1. Preferably at the same time the holes B are stamped out, I cut through the stock along the line C for 50 the length of the piece of stock D, thus forming a tongue which performs the function of a pintle. In order to couple a member to the coupling element just described, it is necessary to "buckle" this coupling 55 element along the line a—a. So buckling

the coupling element forms a clear passage E between the free end of the tongue D and the body-portion of the coupling element, thus enabling the head F of the arm G to be passed through the said passage. The 60 head F is provided with a hole H, and as this head is passed into the passage E, the same is slipped over the tongue D. The coupling element is then pressed back into the position illustrated in Fig. 1, thus preventing the removal of the arm G therefrom. The arm G in Fig. 3 is shown associated with a coupling element in order to show how this arm and the bar I carried thereby (which bar at its opposite end supports another arm G not shown) may be hinged to the door J of the oven K. The lip L of the head F will engage with the bar M carried by the oven to retain the door J closed. The holes B permit of the free 70 movement of the head F for engaging and disengaging purposes in respect of the bar M. In this showing, the tongue D is of sufficient size to easily fit the hole H. A hole 75 G is formed in the door J to permit of the 80 placing of the arm G.

75 In Fig. 4, I illustrate a modified form of my invention. 2 represents a metal plate in which have been formed the holes B¹ and the tongue D¹. 3 is a metal plate provided with 85 a slot 4 through which passes the tongue D¹, thus coupling the plates 2 and 3 together substantially in a position at right angles to each other. From the foregoing part of the specification, without further description it 90 will be understood how the plates 2 and 3 are coupled together. From the disclosure made in Fig. 4 particularly, it will be understood that my coupling element and the method of employing the same may be made 95 use of in various fields, for instance, in connection with mechanical toys. The slot 4 in Fig. 4 is shaped to conform to the tongue D¹, and therefore it will be understood that there will be no movement of the plate 3 on 100 the tongue D¹.

105 At the same time the holes B are formed, if desired I may form the holes 5 in the preferred form of coupling element through which the attaching means therefor passes. The shape of the coupling element is of course, immaterial, as will be understood.

110 While I have described what I consider to be the best embodiment of my invention, I do not confine myself to the construction herein

shown and described, except in so far as that may be necessary by reason of the prior art and the terms of my claims.

One of the principal objects of my invention is to reduce the cost of manufacture of hinges for door handles used particularly in connection with gas stoves, and it will be understood by one skilled in this art, that my disclosure can be manufactured and attached much more cheaply than any other similar coupling element with which I am acquainted.

From the foregoing specification, together with the disclosures made by the drawings, it will be understood that the tongue D, together with the holes B, must essentially be placed within the perimeter of the coupling element.

What I claim as my invention is:

20 1. As a new article of manufacture a coupling element within the perimeter of which has been stamped two alined holes, and a tongue positioned between said holes, the top and bottom edges of which are substantially parallel to each other; one side of said tongue

being severed from said coupling element, but normally resting substantially in contact therewith.

2. The combination with a coupling element provided with two alined holes separated by a tongue, the top and bottom edges of which are substantially parallel to each other, one end of said tongue being severed from said coupling element, which element is designed to be "buckled" on a line passing substantially centrally through said holes and tongue, to provide a passageway through said coupling element, of an element provided with a hole passed into said passageway and coupled to said tongue by means of its hole; the said coupling element, after said second-mentioned element has been positioned, being pressed back into normal position, as set forth.

In testimony whereof I affix my signature in presence of two witnesses.

FREDERICK MACDONALD FAIRGRIEVE.
